UNITED STATES PATENT OFFICE.

JOHN M. BEACH AND GEORGE FLETCHER, OF GRAND RAPIDS, MICHIGAN, ASSIGNEES
TO STROMBERG-CARLSON TELEPHONE MANUFACTURING COMPANY, OF ROCHESTER,
NEW YORK, A CORPORATION OF NEW YORK.

DESIGN FOR A COMBINED RADIO AND PHONOGRAPH CABINET OR SIMILAR ARTICLE.

Application filed March 30, 1927. Serial No. 21,396. Term of patent 7 years.

To all whom it may concern:

Be it known that we, JOHN M. BEACH and GEORGE FLETCHER, citizens of the United States, residing at Grand Rapids, county of Kent, State of Michigan, have invented a new, original, and ornamental Design for Combined Radio and Phonograph Cabinets or Similar Articles, of which the following is the specification, reference being had to the accompanying drawing, forming a part thereof.

The figure is a perspective view of a combined radio and phonograph cabinet or similar article showing our new design.

We claim:

The ornamental design for a combined radio and phonograph cabinet or similar article as shown.

JOHN M. BEACH.
GEORGE FLETCHER.
